DESIGN FOR A CONTROL AND INSTRUMENT PANEL FOR BATTERY CHARGERS OR SIM- ILAR ARTICLE

Merlin L. Pugh, Minneapolis, Minn.

Application April 10, 1945, Serial No. 118,944

Term of patent 7 years

(Cl. D26—1)

To all whom it may concern:

Be it known that I, Merlin L. Pugh, a citizen of the United States and a resident of Minneapolis, in the county of Hennepin and State of Minnesota, have invented a new, original, and ornamental Design for a Control and Instrument Panel for Battery Chargers or Similar Article, of which the following is a specification, reference being had to the accompanying drawing forming part thereof.

Figure 1 is a top plan view of a control and

instrument panel for battery chargers or similar article showing my new design, and

Figure 2 is an edge view thereof.

The dominating features of my design reside in the portions shown in full lines in the drawing.

I claim:

The ornamental design for a control and instrument panel for battery chargers or similar article, substantially as shown and described.

MERLIN L. PUGH.
